UNITED STATES PATENT OFFICE.

HENRY JOSEPH PODLESÁK, OF CHICAGO, ILLINOIS.

ELECTRICAL IGNITION DEVICE.

1,034,645.

Specification of Letters Patent.

Patented Aug. 6, 1912.

Application filed March 25, 1910. Serial No. 551,546.

To all whom it may concern:

Be it known that I, HENRY JOSEPH PODLESÁK, a citizen of the United States, residing at Chicago, county of Cook, and State of Illinois, have invented certain new and useful Improvements in Electrical Ignition Devices, of which the following is a specification, reference being had to the accompanying drawings.

10 This invention relates to electrical ignition devices for explosive engines and the like, and has for its particular object to provide a simple, compact, and effective means for igniting the explosive charges in the cylinders of internal combustion motors.

Referring to the drawings: Figure 1 is a diagrammatic representation of an arrangement for a single cylinder motor; Fig. 2 shows an arrangement for a four cylinder motor; Fig. 3 shows one modification of the circuit making and breaking device; Fig. 4 shows another arrangement for four cylinder motors.

25 Letter G represents a magneto generator, having permanent magnets M, and pole pieces L L, between which rotates, or oscillates, the armature core I, which carries generating windings W, all being of the usual arrangement in magneto generators, except that the windings should have comparatively high inductive capacity.

30 Letter T represents a transformer, having primary windings P and secondary windings S, the two being in inductive relation to each other. The conductors 8 and 9 connect the secondary to the electrodes e and e' of the spark plug, in which q is the spark gap.

40 One terminal of the primary is connected to one terminal of the generating windings by conductor 3, the other terminal of the primary being connected to the other terminal of the generating windings by conductor 2, through condenser C, and conductor 1, the condenser being in series with the two conductors. The circuit is W—1—C—2—P—3—W. Conductor 5 connects conductor 1 to one terminal of a circuit making and breaking device, the other terminal of which is connected to conductor 3 by conductor 4.

45 In the circuit making and breaking device, k is a cam which is suitably journaled and driven in synchronism with the armature shaft; the cam has suitable cam sur-

faces on its periphery to vibrate the pivoted arm b through means of a roller carried by b and riding on the cam surfaces; the arm b is pivoted at h and carries a contact point c, which is adapted to make contact alternately 60 with contact points m and n which are carried by frame f; m and n are not insulated from each other. The spring z serves to keep the roller in contact with cam surfaces.

50 As shown in Fig. 1, the roller of arm b has just entered a depression in the cam surface, thus allowing the arm b to move to the left until the contact point c has made contact with n; just below the roller the cam surface is shown raised, the raised portion 70 being at such distance, or radius, from the center of the cam journal that the arm b will be moved to the right, when this raised portion of the cam moves under the roller, to such extent that the contact point c will 75 contact on m. The remainder of the cam surface may be at such radius that the arm b is moved into, and maintained at, such position that the contact c stands midway between m and n, out of contact. This 80 would be desirable when batteries are used as source of current, to prevent unnecessary drain on the batteries.

55 The operation of the whole apparatus is, referring first to Fig. 1, as follows: Electrical pressure is generated in the armature windings when the armature is rotated; at a proper period, the cam k, which is rotated simultaneously with the armature, (and in synchronism with the armature in the case 90 the generator generates alternating current of comparatively low frequency, which would be the case in the type of generator shown), causes the arm b to move so that c makes contact with one of the contact points, say n, then to break the contact and immediately make contact with the other contact point m, assuming the cam to revolve counter clockwise. Now, as soon as the contact has been made on n, a heavy flow of current will be established through, or in, the generating windings, the circuit being W—1—5—b—f—4—3—W; since the generating windings possess inductance, energy will be stored in them; then, as the circuit is broken at n, an inductive impulse of comparatively high potential will discharge from the windings through the primary P into the condenser C, which will become highly charged, and again discharged, through the primary 105 110 115

P and the circuit making and breaking device, immediately the arm *b* makes contact on *m*. Thus, there is a heavy flow of current rapidly established through the primary winding of the transformer just after 5 the contact is broken at *n*, the condensance of *C* being made of suitable capacity with respect to the inductance of *P* so that there is no lag in the current flow; this heavy flow of current through primary *P* induces high 10 electrical pressure in the secondary *S*, from the terminals of which conductors are led to the spark plug terminals, *e* and *e'*, the electrical pressure being high enough to cause current to jump across the air gap *g*, which, 15 in practice, is inside the motor's cylinder, where the arc, established across the air gap, will ignite the explosive charges therein. Coming now to the action that takes place 20 when contact is made at the contact point *m*, it will be readily understood that as soon as contact is made at *m*, which will be immediately after contact is broken at *n*, the condenser, which has just been highly charged, 25 will discharge through the circuit making and breaking device and the primary, (the circuit being *C*—2—*P*—3—4—*f*—*b*—5—1—*C*—), inducing further electrical effects in 30 the secondary *S* of nearly the same magnitude as those induced by the discharge from the generating windings. Thus, high electrical pressure, sufficient to cause current to jump across the air gap of a spark plug is induced in the secondary winding, first, 35 when the contact is broken at *n*, and again when contact is made at *m*. Either of these electrical effects, the one produced on breaking contact, or the one produced on making contact, is amply sufficient, when a suitable 40 generator, or other source of current is used, to effectively ignite the explosive charges in internal combustion motors. Hence, one of the stationary contact points may be left off as is shown in Fig. 4, and the electrical effect produced on breaking contact alone 45 used for the ignition of the explosive charges. However, I prefer to use the two stationary contact points scheme, or equivalent action, since it appears to give somewhat better results at low speeds of the 50 armature.

It will be observed that, whenever the arm *b* of the circuit making and breaking device makes contact on one of the stationary contact points, two complete circuits are made, 55 namely, circuit *W*—1—5—*b*—*f*—4—3—*W*, on the left side of said device and circuit, *C*—2—*P*—3—4—*f*—*b*—5—1—*C*, on the other or right side of the device. Current 60 may flow in both circuits at the same time if there be difference of potential at the terminals of the generating windings and of the condenser. The condenser is, of course, charged to the potential existing in 65 the generating windings just before the con-

tact is made by *b*, and discharges as soon as the contact is made, the current flowing through the primary in such direction as to magnetize, to a slight extent, the magnetic field of the primary in the reverse direction 70 to that produced by the inductive discharge from the generating windings; there is thus a greater flux variation produced in the magnetic field of the primary of the transformer than would be by the inductive discharge alone, and hence also greater electrical effects are produced in the secondary 75 winding.

The arrangement shown in Fig. 2 differs from that shown in Fig. 1 only in that 80 it is adapted for a four cylinder motor. The cam *k* has four lobes so as to produce four movements of the arm *b* for each revolution, one movement for each cylinder. The distributor blade *F* revolves at the same speed as the cam, preferably on the same shaft with the cam; it makes contact, at proper periods, with any one of the segments *s*, thus connecting the secondary circuit with the spark plug of that cylinder 90 which is in period for ignition. For the type of the generator shown, the cam and the distributor are to run at half speed of the armature for four cycle motors.

Fig. 3 shows a modified form of circuit 95 making and breaking device in which only one stationary contact point is used. The action is the same as in Figs. 1 and 2, since the contact is maintained when the roller is on the high portions of the cam and broken 100 only for an instant as the roller rides into the depression on the cam surface.

Fig. 4 shows a modification of the arrangement in which four transformers are used, one for each cylinder and preferably 105 placed on or near the cylinder; in this arrangement the distributor is placed in the primary circuit and it switches the primary current to the transformer operating the cylinder that is in proper period for 110 ignition. The action of the circuit making and breaking device shown in Fig. 4 is such, at slow speeds, that the inductive discharge of the generating windings alone is 115 utilized for producing the electrical effects in the secondary of the transformer. The heavy flow of current in the generating windings is established when the roller of arm *b* rides into the depressions in the cam *k*, the circuit being then made on *m*, and broken as soon as the roller rides onto the high portion of the cam.

The circuit making and breaking device of Fig. 2 may be used in the arrangement of Fig. 4, and vice versa. Also, the circuit 125 making and breaking device and the distributor may be combined into one, by providing four contact arms *b* and four stationary contact points, both, the arms and points, properly spaced around the cam, 130

which would, in this case, have only one depression, to operate the various arms alternately.

While I have shown a generator as source of current, it is obvious that batteries may be substituted, though, when batteries are used, a coil having inductance must be included in the battery circuit, that is, between the battery and the circuit making and breaking device.

What I claim as my invention, and desire to secure by Letters-Patent is:—

1. In an ignition system, the combination of a condenser, a primary winding connected in series relation with the condenser and adapted to be energized by a high potential impulse charging the condenser, a secondary circuit inductively related to the winding and including a sparking device, a supply circuit connected with the condenser and winding and including inductance to produce the high potential impulse for charging the condenser upon the momentary closing and opening of the supply circuit, 25 a shunt around the condenser and winding, and means for closing and opening in quick succession the circuit through the said shunt.

2. In an ignition system, the combination of a supply circuit of alternating current including inductance, means for momentarily closing the circuit as the electromotive force approaches its maximum value and for quickly opening the circuit to produce an impulse due to the inductance, a condenser charged by such impulse, a primary winding traversed in series relation and energized by the condenser charging impulse, and a secondary circuit inductively related 40 to the primary winding.

3. In an ignition system, the combination of a supply circuit including inductance, a condenser and a primary winding in series in the circuit, a shunt across the circuit in parallel relation to the condenser and winding and a circuit make and break device for first closing the circuit through the shunt to store up energy by the inductance and then opening the shunt to cause 50 a high potential impulse through the winding and condenser due solely to the inductance for energizing the winding.

4. In an ignition system, the combination of a supply circuit including inductance, a condenser and a primary winding in series in the circuit, a secondary circuit including a sparking device, a shunt around the condenser and winding, and a make and break device in the shunt, and a device consisting of a contact connected with one side of the circuit and a pair of contacts connected with the other side whereby the shunt is in quick succession closed and opened and again closed and opened to effect a rapid charging and discharging of the condenser for each ignition period of the engine.

5. In an ignition system, the combination of a supply circuit containing inductance for producing upon the opening of the circuit, a high potential impulse, a condenser for receiving such impulse, a primary winding in series relation with and traversed by the impulse during the charging of the condenser, a secondary circuit including a sparking device, a shunt around the condenser and winding, and a make and break timing device for first closing the circuit and instantly opening the same to produce the impulse to charge the condenser through the winding, and again closing and opening 80 the circuit to discharge the condenser through the winding for producing two sparks at each ignition period of the engine.

6. In an ignition system, the combination of a magneto, a condenser and a primary winding in series with the winding of the magneto armature, a shunt around the primary winding and armature, a make and break device in the shunt and including a movable contact element, and an actuator 90 for moving the element in timed relation to the armature to effect in quick succession the closing of the circuit as the armature attains an approximate position of maximum electro-motive force and the opening 95 of the circuit to obtain a high potential impulse through the winding in charging the condenser.

In testimony whereof I affix my signature in the presence of two subscribing witnesses. 100
